UNITED STATES PATENT OFFICE.

JOSIAH BRADLEY, OF NEW YORK, N. Y., ASSIGNOR TO ALBERT WESTLAKE, OF NEW YORK, N. Y.

BOTTLE CAPPING AND SEALING MACHINE.

1,120,017.

Specification of Letters Patent. Patented Dec. 8, 1914.

Application filed January 11, 1911. Serial No. 601,938.

To all whom it may concern:

Be it known that I, JOSIAH BRADLEY, a citizen of the United States, and a resident of Brooklyn borough, New York city, and 5 State of New York, have invented certain new and useful Improvements in Bottle Capping and Sealing Machines, of which the following is a specification.

The object of my invention is to provide 10 a strong and reliable bottle capping and sealing machine, by means of which a piece of capping material may be rapidly and accurately pressed into and around the mouth of the bottle and so shaped and forced into 15 intimate contact with the same, as to provide a perfect air tight closure. It is more particularly adapted and intended for use in bottling milk and other liquids which do not generate internal pressure; the seal being required to be thoroughly hygienic and 20 sanitary, but it is also adapted to provide an effective seal, for charged water and other liquids, which generate internal pressure. This difference in the use of my invention 25 proved machine, depends rather upon the material of which the cap is made, than upon the mechanical construction of the machine itself.

In capping milk bottles, as is well known, 30 the cap is intended to be easily removed, within twenty-four hours or so, of bottling, the milk meanwhile being protected from leakage, from absorbing deleterious or other odors and from the entrance of any dirt or 35 other substance which might impair the quality of the milk. Such caps are therefore, usually and preferably made of paper or other fibrous material. In capping charged waters, beer, ale, and other charged 40 liquors, the caps are usually and preferably made of metal with or without an inner seal, of other material, owing to the fact that the contents may have to remain undisturbed for a considerable length of time 45 before using. The method of applying the cap by my improved machine, however, is the same in both cases and consists briefly in depressing the central portion a reasonable distance into the mouth of the 50 bottle, so as to make a snug fit on the inside of the bottle neck, and at the same time, turning the outer portion of the material, down around the outside of the bottle neck, and tucking the edge in under the 55 bottle neck ring. During this movement,

the plunger fingers, iron, so to speak, the cap into intimate contact with the outside of the bottle neck, above, around and below the bottle neck ring, so that when the plunger is with-drawn, the cap remains on the 60 bottle as a perfectly air tight seal, capable of withstanding both internal and external pressure, by the combined action of atmospheric suction and frictional contact.

In the accompanying drawings, I have 65 shown my invention in very simple form, as applied to milk bottles, and for simplicity of illustration, have shown what is known as an individual bottling machine operated by foot-power. It is to be understood, that 70 steam, electricity, or any other power may be used to operate my machine, and that by increasing the number of plungers a corresponding number of bottles may be capped simultaneously.

Figure 1, is a side elevation partly in section of the machine. Fig. 2, is an enlarged cross section of the plunger, engaging the top of the bottle. Fig. 3, is a bottom plan 75 of the plunger by itself.

The same letters indicate similar parts in the different figures.

A, is the frame work of the machine, consisting of the usual base B adapted to 80 rest on or be fastened to the floor, and provided with the hollow posts C C through which the plunger rods D D slide under the action of the treadle E and the return spring F. G, is the plunger head secured to the top of the rods D D. All these parts 85 being of usual construction, will, I think, be readily understood without further description.

H, is a milk bottle resting on the stand or platform J in position to be acted upon 90 by the plunger, K in its descent. This plunger (see Figs. 2 and 3) consists primarily, of a cylindrical body a, preferably of steel, and a large number of fingers b b, radially arranged around the lower end of 95 said cylinder. The top of this hollow cylinder, is preferably screw-threaded as at c, by which it is secured, to the stub or shank d which is secured in the plunger head by a screw e. (See Fig. 1).

Inside the hollow cylinder, slides the plunger tube, f, the inner end of which is screw threaded to the freely sliding disk, g, set in the chamber h, inside the hollow cylinder a, and somewhat larger in diam- 100

105

Inside the hollow cylinder, slides the plunger tube, f, the inner end of which is screw threaded to the freely sliding disk, g, set in the chamber h, inside the hollow cylinder a, and somewhat larger in diam- 110

eter than the channel through which the plunger tube slides. The tube is provided at one side, with a longitudinal slot *j*, into which enters the set screw *k*, through the body of the cylinder *a*, and thus prevents the tube from turning. The plunger tube, is normally held in its extended position as shown in Fig. 2, by the coiled spring *i*, and the lower end is shaped 10 to correspond with the mouth of the bottle to be sealed, due allowance being made for the material out of which the cap or seal is formed and which has to be pressed into intimate contact with the inside of the 15 mouth of the bottle. The buffer ring *m*, of slightly elastic material, is provided in the lower end of the plunger tube, to aid in pressing the seal, into intimate contact with the top of the bottle. The action of this 20 part of the plunger, is as follows: The end of the plunger tube, is first brought down to rest squarely on the cap which has been placed on the top of the bottle, and pressure is then applied by the descent of the plunger 25 cylinder, *a*, which contracts the coiled spring *i*, in its descent. Practically, the plunger cylinder never descends low enough to strike against the flange of the plunger tube, but the resilient force of the spring *i*, constantly 30 increasing with its compression transfers the pressure of the stroke to the material of the bottle cap, and forces it into as close contact with the bottle, as its character will allow. During this downward stroke, the 35 coiled spring, *n*, which surrounds the plunger cylinder, is also compressed, with the result that when the plunger ceases to descend the cylinder rises first and the tube follows; the spring *n*, being considerably 40 heavier than the spring *i*.

As before stated, the lower part of the cylinder, *a*, is surrounded by a multiplicity of fingers, *b*, *b*, radially arranged. The purpose of these fingers, is not only to tuck the 45 outer edge of the capping or sealing material, in under the bottle neck ring, but to press the material into intimate contact at all points with the outside of the bottle. The effect produced is a sort of ironing, 50 especially if the capping material has been pre-heated, and therefore, the action of these fingers, must be regular, accurate, and steady. To bring this about, I suspend the fingers at their upper ends on a pivotal ring 55 *o*, upwardly projecting from the flange of the cylinder *a*, so that they are free to swing in or out as occasion requires. To permit a limited in and out swing and to prevent any lateral displacement, I surround 60 this circle of fingers by two rings or bands, *p*, *s*. Each of these rings has a number of inwardly projecting fins or thin plates *p*, corresponding to the number of fingers so 65 that the fins alternate with the fingers and by occupying the space between them pre-

vent any lateral motion of the fingers. The lower band *s*, has a beveled mouth or recess which not only acts as a centering bevel to guide the plunger upon the bottle top, but also receives and holds the cap or capping disk and places it on the bottle-top. The lower end of the fingers *b*, is always held pressed inwardly by the flange *v*, which is fixed upon the plunger cylinder in such position as to rest against the top rib of the 75 fingers.

The complete operation of sealing or capping a bottle by the above described machine, is as follows: The bottle being placed upon the stand *J*, immediately under the plunger, which is in its raised position, a cap or capping disk is then either laid upon the bottle-top, or set in the plunger mouth as preferred. The treadle is then forced downward drawing the plunger down upon the bottle. The first operation of the plunger is to seize the center of the cap or disk, and force it into the mouth of the bottle, and simultaneously, to press a portion of the capping material upon the upper edge 80 of the bottle, by the elastic gasket *m*. As the plunger continues to descend, the cylinder *a*, creeps down along the tube *f*, thus steadily increasing the pressure of the plunger tube upon the inside and top of the 85 bottle mouth, while simultaneously the lower ends of the fingers creep by the end of the plunger tube, and begin to force the outer portion of the capping material down and around the outside of the bottle neck. 90 This action continues as the plunger continues to descend until the fingers have molded the capping material in under the bottle neck ring and the plunger reaches the end of the downward stroke. Pressure on 95 the treadle is now removed, and the plunger head and plunger are drawn upward by the contractile force of the spring *F*. As the plunger rises, the fingers being their return 100 or upward trip under the action of the resilient force of the spring *n*; still retain their ironing pressure, against the bottle cap until they leave the top of the bottle, and begin to creep up the side of the plunger tube. During all this time, the plunger tube 105 has been held down against the cap by the resilient force of the spring *i*, but as the plunger cylinder has now reached the point where it picks up the disk *g*, the plunger tube begins to be lifted away from the 110 bottle, and the capping is complete. At the end of the upstroke of the plunger the capped bottle is removed and a fresh bottle uncapped put in place ready for the next 115 downward stroke.

I claim:

A bottle capping and sealing machine provided with a plunger comprising a hollow plunger-cylinder adapted to be set in the plunger-head of said machine, and hav- 120

ing an upturned flange-ring on its exterior surface; a spring actuated plunger-tube located in said hollow cylinder and terminating in a die adapted to force the central portion of the sealing material into the mouth of a bottle neck placed thereunder, and hold the same in close contact with the top and inner wall of said neck; a circle of independent tucking fingers radially arranged around said cylinder and resting upon said up-turned flange-ring; annular bands attached to said cylinder and inclosing said circle of radial fingers and provided with internally projecting fins adapted to enter the spaces between said fingers; and a spring-controlled annular plate loosely surrounding said cylinder and resting upon the tops of said radial fingers; the spring which actuates said annular plate being of heavier caliber than the spring which actuates the plunger-tube, whereby in the operation of said plunger, said plunger-tube is caused to continue its downward pressure until the pressure on the cylinder is released. 20

JOSIAH BRADLEY.
